AUTOMATIC RADIO STATION SELECTOR

John E. McCarthy, Tuckahoe, N. Y.

Application August 19, 1936, Serial No. 96,749

13 Claims. (Cl. 250—20)

This invention relates to improvements in means for controlling the operation of radio sets, and one of its objects is to provide means for automatically selecting different stations, at predetermined periods, so that a program of broadcasts can be carried out, without detail manual supervision after the initial selection of stations is made.

A further object of the invention is to provide a time controlled mechanism for automatically selecting different stations in proper timed sequence, so that at the announced time for each station in the selected group such station will be tuned in, and the radio set will continue to operate.

A further object of the invention is the provision of such a mechanism with means for causing a pause between stations.

A still further object of the invention is to provide a driving connection between the individual station selector elements and the tuner, so that continuous rotary motion of the station selector elements may be maintained and an oscillating motion of the tuner generated in proper synchronism with the movement of the individual station selectors.

A further object of the invention is to provide individual station selector wheels, having circuit connections and contacts so arranged that successive circuit controlling operations are accomplished in proper timed relation.

A still further object of the invention is the provision of a series of individual station selector bars, each one of which is constructed to provide short time interval selections, and circuit connections between the active station interval positions of the bars with the rotary station selector discs.

The invention also comprehends means for automatically closing the circuit through a radio set and of operating the tuning element therefor to render any particular station audible, and for automatically cutting out such station at the end of a predetermined period of time.

The invention further comprehends means for automatically controlling the period between the program received by the radio set and the period for the starting of the program of another broadcast station, so that an interval of silence may be obtained.

With the above and other objects in view the invention relates to certain new and useful constructions, combinations, and arrangements of parts, clearly described in the following specifica-

tion, and fully illustrated in the drawings, in which:

Fig. 1 is a diagrammatic view showing the time controlled circuit and the operating circuit closures and means therefor.

Fig. 2 is a detail side view of an operating connection between the main shaft and the radio set tuner.

Fig. 3 is a detail side view of a modified operating connection.

Fig. 4 is a diagrammatic view showing the circuit between the timing bars and the clock.

Fig. 5 is a detail side view, enlarged, showing a graduated timing bar.

Fig. 6 is a detail end view of one of the slides which controls the different connections of the timing bars.

Fig. 7 is a detail cross section of a contact bar.

Referring to the accompanying drawings a radio set 7 is arranged, which may be of any construction, and of any number of tubes. This set is merely indicated and not shown in the drawings, and includes a tuning element, or tuning condenser 8, which has an operating shaft 9. On this shaft the disc 10 is mounted, and this disc is equipped with a lateral pin 11, which is engaged by the end of the link 12. This link engages at its opposite end the pin 13 of the disc 14, which is mounted on the main shaft 15 of the controlling device. The disc 10 is larger than the disc 14, so that disc 10 will never make a complete revolution.

The main shaft 15 works in bearings 16 and 17, and carries seven circuit closure discs or drums, indicated at 18, 19, 20, 21, 22, 23 and 24. The disc or drum 18 is provided with a hub 18a, which is secured for circumferential adjustment on the shaft 15 by means of the set screw 18b. Each of the other discs or drums is provided with a similar hub 25a, which is secured for circumferential adjustment on the shaft 15 by means of the set screw 25b.

The disc or drum 18 is provided with a metal ring or band 18c, which is formed with an edge notch 18d. This band is mounted on a circular body of insulation 18e. The metal band or ring 18c is engaged by a contact element 18f, which maintains unbroken metallic engagement with the metal ring or band. Another contact element or spring 18g also engages the band or ring 18c but is so located that it will ride over the edge notch 18d, and thus break the circuit through the drum or band 18c.

The disc or drum 19 is provided with a circular body 19a of insulation material, and is equipped

with an annular metal band or member 19a, which is formed with a lateral edge notch 19b. This member 19a is also formed with a lateral contact finger or tooth 19c, which is located 5 in the same circumferential position as the lateral edge notch 19b. This drum is further provided with a contact insert 19e, disposed in the same circumferential position as the notch 19b and the tooth 19c, and insulated from the tooth 10 19c. The metal band or member 19a is engaged by the spring contact fingers 19f and 19g. The contact finger 19f is adapted to ride over the edge notch 19b, and the finger 19g maintains constant metallic engagement with the band or member 15 19a. This drum 19 is further engaged by the two spring finger contacts 19i and 19j, and these contacts are located so that they will engage the contact insert or bridge 19e at the same time, and the spring finger 19h is located between the 20 contact fingers 19g and 19i and is adapted to contact with the lateral conductor tooth 19c.

Drums 20—24 and their associated brushes are similar in construction to drum 19, with the exception that the elements corresponding to 19b, 25 19c and 19e of one drum are all circumferentially offset with respect to all the similar elements in the other drums.

The shaft 15 is equipped on one end with a worm gear 25, which is engaged by the worm 30 shaft 26. This shaft is provided with a large pulley 27, which is driven by means of the belt 28 from the small pulley 29 of the electrical motor 30. The shaft 26 works in the bearing 26a.

One terminal of the motor is connected by the 35 wire 31 with contact finger 18f of the drum 18; with the contact finger 19g of the drum 19; with the contact finger 20g of the drum 20; with the contact finger 21g of the drum 21; with the contact finger 22g of the drum 22; with the contact finger 23g of the drum 23; and with the contact finger 24g of the drum 24. The other terminal of the motor is connected by the wire 32 with the supply line wire 33. The other line wire 34 is connected to the wire 35 and to the switch 45 36. A feed wire 37 connects this switch 36 with the electrical motor which operates the clock 38, and the return wire 39 of this clock is connected with the wire 40, which is directly connected with the 40 7 watt indicating lamp 41. The wire 42 is connected with the wire 40 and supplies current to the radio set, the return wire 43 of which is connected with the second switch 44.

The switch 36 is adapted to make contact with the contact 45 of the wire 46, and the switch 44 55 is adapted to make contact with the contact 47 of this wire 46. The wire 46 is connected to the contact member 48 of the thermostatic switch 49. One end of the member or bar 48 is provided with a contact 48a and the other end is provided 60 with a contact 48b. These end contacts are engageable by the contacts 50a and 50b of the companion contact bar 50, on which is wound the electrical heating or resistance wire or coil 51. A manually operated button or element 52 is 65 adapted to move the contact 50a into engagement with the contact 48b. One end of the resistance wire 51 is connected to the wire 53 of the indicating lamp 41, and the other end is connected 70 to the wire 54, which is connected with the fifteenth minute contact elements 55, 56, 57 and 58 of the clock 38. These contact elements are spaced 90 degrees from each other and are successively engaged by the minute hand 60 of this 75 clock. A series of 48 fifteen minute contacts 61

are arranged in a circular row to be engaged successively by the hour hand 62 of this clock.

A wire 63 is connected with the wire 53, which has connection with the indicating lamp 41 and with the resistance wire 51, and this wire 63 is provided with a contact 64 which is engaged by the manually operated switch button 65, to cause the contact 64 to engage the contact 66. The contact 66 is wired directly to the contact bar 50 and is also connected with the resistance wire 10 51.

Wire 67 connects wires 53 and 63 with the "off" station bar 68.

I provide one station setting bar for each drum and an additional setting bar, for controlling the 15 time period for stopping the audible operation of the radio set, the latter being the bar 68. The bar 69 is connected by the wire 70 with the contact finger 24f of the drum 24; the bar 71 is connected by the wire 72 with the contact finger 20f of the drum 23; the time bar 73 is connected by the wire 74 with the contact finger 22f of the drum 22; the bar 75 is connected with the spring contact finger 21f of the drum 21, by the wire 76; the bar 77 is connected by the wire 78 with the spring contact finger 20f of the drum 20; the bar 79 is connected by the wire 80 with the spring finger 19f of the drum 19; and the bar 82 is connected by the wire 83 with the spring contact finger 18g of the drum 19.

Each of the bars is metallic or provided with a metallic conductive strip, which is engaged by the slide 84. One or more slides may be arranged on each bar. The bars are arranged in parallel relation to each other, and disposed 35 horizontally.

The intermediate fingers 19h, 20h, 21h, 22h, 23h, and 24h of the drums 19, 20, 21, 22, 23 and 24 are connected by the wire 85 to the switch 36, in series with the indicating lamps 19', 20', 40 21', 22', 23' and 24', which are about 7 watt capacity. The spring fingers 19i, 20j, 21j, 22j, 23j, and 24j, of the drums 19, 20, 21, 22, 23, and 24 are connected by the wire 86 to the switch 44.

The forty-eight contact elements which are 45 engaged by the hour hand are wired to forty-eight conductor strips 87, which are arranged in parallel relations, spaced apart from each other as shown in Fig. 3, at right angles to the time bars, so that each of these conductor strips 87 50 can be engaged by any of the slides on any of the time bars, and circuit thus established between the time bar of the engaging slide and the engaged clock conductor strip 87.

A brake drum 88 is provided on the main shaft 55 15, which is engaged by the brake or friction band 89, so that there will be no momentum generated by the drums on this shaft.

To start the automatic operation of the time controlled radio set, the line switch 36 is closed, 60 and at the same time the On button 52 is held depressed. This will cause the current to flow from line wire 34, through 35, 36, 45, 46, contact 48b, contact 50a, strip 50, heating coil 51, wire 53, lamp 41 to line wire 33. The On button 52 65 is then released, but the heating coil 51 remains energized, due to the fact that the thermostatic switch contacts remain fully engaged. This condition causes the current to flow to the wire 54, 70 and to the clock contacts 55, 56, 57 and 58 of the minute hand 60. These four fifteen minute contacts are connected electrically to each other, so that when the minute hand engages one of these contacts current will flow through the minute hand, to the hour hand 62, which is in conduc- 75

tive contact therewith, and to the contact 61 engaged by the hour hand, and thence to the wire 87 connected therewith, and thence to the cross slide wire or strip connected with this wire. Current will then flow to the slide of the bar engaged with this cross wire or strip to the bar of this slide, which is itself conductive, and thence to the distribution wire which leads from this bar to the rotary drum contact connected therewith.

10 In the event that the station bar 19 is active, the current will flow from this station bar to the wire 89, to the contact finger 19f, to the conductor band 19a, to the contact finger 19g, and to the wire 31 to the motor 30, from motor through 32 to the line wire 33 which completes the motor circuit.

15 When the motor has rotated the drum shaft 15 to bring the edge notch 19b into engagement with the contact finger 19f, the motor circuit will be opened, thus causing the motor to stop, due to the frictional drag of the tension drum 88 upon the motor. At the time the edge notch 19b engages the finger 19f the lateral tooth 19c of the drum 19 will be engaged by the intermediate finger 19h, and current will flow from line wire 34, 19h, and 35 through lead wires 35 and 85, indicating lamp 19' of the drum 19, into finger 19h, tooth 19c, band 19a, finger 19g, wire 31, through motor 30, to wire 32, to line wire 33 which completes the circuit. Due to the fact that the indicating lamp is in series circuit with the motor 30, the motor, though energized, will not have sufficient current to rotate, and due to the fact that the power circuit through the motor was broken when the edge notch 19b engaged the spring contact finger 19f, the shaft 15 will remain idle with the motor 30.

20 With the drum in this position, circuit is established between the spring contact fingers 19i and 19j, which then connects the load side of the switch 44 by way of wire 86, finger 19j, bridge contact 19e, finger 19i, wire 86a, bar 50, contacts 50b and 48a, bar 48, wire 46, switch 36, wires 35 and 34, and energizes the receiver at the station controlled by the drum 19. At the end of the time period predetermined upon for the broadcasting of the program of the station controlled by the drum 19, the thermostatic contacts are caused to separate by the action of the clock, which causes a metallic shunt across the heating coil 51 which then loses its ability to keep strip 50 expanded and thereby causes contacts 48a and 50b to open. The shunt circuit across the heating coil 51 is through wire 54, clock contacts 55, 56, 57 or 58, hand 60, hand 62, contact 64, through slide 84, to bar 68, "off" wires 67, 53 to other end 55 of heating coil 51. The set will then remain "off" until reset. Button 65 with its contacts 64 and 66, also creates a shunt across heating coil 51 and is used for test purposes or in making a change to the automatic operation from the manual operation. The turning "off" or "on" of the radio set may be had by simply opening the line switch 36.

When a station drum has been automatically cut out by the above operation, the clock will continue to operate, and at the next starting time period, as selected by the arrangement of the slide or slides on the station bars and pressing of button 52, the clock will again establish circuit through the motor, and the shaft 15 will be turned so that the drum of the station to be next received will make the necessary circuit connections to close the radio tube circuit and to stop the motor, as above indicated.

When no program is desired for a particular station or time period, the automatic control may

be continued, through the aid of the pause drum 18 and its bar 82. Drum 18 is devoid of equipment for lighting an indicating light and fingers for energizing the set tubes. Drum 18 is set upon the shaft 15 in such a way that it will turn the tuning condenser to a position off the automatic setting. The time period at which the pause drum operates is determined by the bar and the pause bar slide thereon, just as in the case of the other drums and their time bars.

The drums are adjusted so that the machine will operate properly with reference to the local or other stations connected in. Since any radio station is brought in by turning the tuning knob of the set, so that the tuner is given an adjustment corresponding to the wave length of the station, it follows that if the controlling drum of any station is adjusted on the shaft 15 so that a similar turning effort is obtained from the motor, before it automatically stops, that this station will be received, when the set tubes are energized properly.

My invention thus provides means for automatically selecting one or a series of programs from the same or different stations, and for automatically rendering the radio set audible at the selected time periods, so that the stations will be heard as desired or selected. My invention thus provides an automatic program control for radio sets, which does not require that a person make different manual operations, each time the set is to be adjusted to receive a different program or a different station. By operating the knob on the end of the shaft 26 the drum shaft 15 may be manually turned, so that the automatic control is cut out; or by pressing the Off button 65.

I claim as new and patentable:

1. The combination with a radio set having an adjustable tuner to change the wave length of the radio set to receive broadcasts of different radio stations, of a shaft having a differential operating coupling with the tuner, a plurality of drums on the shaft, contact fingers engaging each drum, a plurality of station bars, adjustable electrical contacts on the station bars, a clock controlled circuit closer, a motor for turning the shaft, said clock control circuit being arranged to connect each of the said bars to the line in sequence, whereby with any given setting of the electrical contacts, circuit will be made through the motor as soon as the time bar connected to said drum is energized and continue until the drum is rotated to a point of circuit breaking and means on said drum at the point of circuit breaking for automatically re-routing the motor circuit after 55 tuning in, through the motor in series with an indicating lamp, thus providing an indication and cutting down the motor current below the operating margin.

2. The combination with a radio receiving set having an adjustable tuner, of an operating shaft, a driving connection between the shaft and the tuner, whereby the tuner will be turned less than a complete revolution, a motor for turning the shaft, a time mechanism having a series of spaced contacts corresponding to different time intervals and a moving element to successively engage said contacts, a series of time selectors, a circuit closer on the shaft having circuit connections with each time selector, electrical conductors having circuit connections with the spaced contacts of the time mechanism, adjustable contacts on the time selectors for engaging any one of the electrical conductors, said motor being connected in series with said spaced contacts, said moving

- elements, said time selectors, said circuit closers and said adjustable contacts, whereby with any selection, said motor will be operated when the time selector is energized, to automatically 5 route the motor circuit after tuning in, through the motor in series with an indicating lamp, thus providing an indication and cutting down the motor current below the operating margin, and means for energizing the radio set effective upon 10 the completion of the reduced operating circuit.
3. The combination with a radio receiving set having an adjustable tuner, a shaft having driving connection with the tuner, a series of drums on the shaft, each drum having a conductor band 15 formed with an edge notch in one side and a contact tooth on the opposite side in line with the edge notch and also having a contact bridge insulated from the band and tooth, contact fingers for each drum including two contacts adapted to 20 simultaneously engage the conductor band so that one of said fingers will engage the edge notch when the drum is rotated, contact fingers adapted to simultaneously engage the contact bridge of the drum, a contact finger arranged to engage the 25 contact tooth, time selecting mechanism having circuit connections with the contact fingers, a motor having circuit connections with the first named contact fingers and circuit connections between the radio set and the last named contact 30 fingers.
4. The combination with a radio receiving set having an adjustable tuner, a shaft having driving connection with the tuner, a series of drums on the shaft, each drum having a plurality of circuit 35 closing means, a plurality of pairs of contact fingers engaging each drum to simultaneously engage said circuit closing means, a motor for turning said shaft, circuit connections between the motor and certain of the contact fingers, circuit 40 connections between the radio set and certain other contact fingers, and means included in the circuit of the motor for holding said circuit closed by thermostatic action and for reducing the flow of current to the motor below the current quantity 45 required for turning the motor.
5. The combination for a radio set having a movable tuner with a shaft coupled to the tuner, a motor for driving said shaft, a plurality of adjustable drums upon said shaft having contacts 50 for controlling the motor circuit, each of said drums being adjustable independent of all others, a plurality of station bars which contact with one of said drums, a plurality of time bars each adapted to be selectively coupled with one of said 55 station bars, a clock adapted to make momentary contact with said time bars in time sequence at the beginning only of said time interval and means for maintaining said circuit closed during the remainder of said time interval, said means 60 including an indicating lamp in series with the motor and adapted to be automatically cut into the motor circuit, thus providing an indication and cutting down of the motor current below the operating margin.
6. A device in accordance with claim 5, in which each drum is provided with a contact for connecting the radio set to the power line only at the time when the shaft is stopped by the contacts on said drum.

7. A control device for radios having a tuning element comprising a shaft in driving connection to said tuning element, a motor for driving said shaft, a plurality of drums on said shaft each having a contact piece arranged to contact with a finger, to form a circuit controlling pair, means for selectively placing any pair in series with the drive motor comprising a plurality of station elements and a plurality of time elements adapted to be selectively coupled into the motor circuit, a 10 clock having a contact connected to said time elements and arranged to place said time elements in the motor circuit in sequence, a pair of contacts arranged in the motor circuit adapted to make circuit momentarily at the beginning of each time 15 interval to start said motor by said momentary current, and means for thereafter holding the motor circuit closed, releasable when the clock contact leaves said time element.
8. The combination with a radio set having a 20 movable tuner and a shaft coupled to the tuner, of a motor for driving the shaft, a plurality of station selectors adjustably mounted upon the shaft and having contacts for controlling the motor circuit, a corresponding number of station 25 bars severally electrically connected to said contacts, a plurality of time bars each adapted to be selectively coupled with one of said station bars, a clock adapted to make momentary contact with said time bars in time sequence at the beginning only of the time interval, an indicating lamp, an initiating circuit for effecting connection with a given pre-selected station, a holding circuit for retaining the selected station for a given time interval, part of the initiating circuit 30 being common to the holding circuit, the individual branch of the initiating circuit including said clock, time bars, selector bars and certain of the selector contacts of a given selector, the individual branch of the holding circuit including only the indicating lamp and certain other contacts of said selector in series, means for substituting the individual branch of the holding circuit for the individual branch of the initiating circuit, and means for interrupting the holding circuit 35 at the expiration of the time interval.

9. A device in accordance with claim 8 in which motor control circuits are cut in by the action of a heating coil expanding a contact member controlled thereby, thus completing the initiating 50 circuit.

10. A device in accordance with claim 8 in which motor control circuits are cut off by a shunt being placed across the heating element of a thermostatic switch for controlling the initiating circuit.

11. A device in accordance with claim 8 in which the circuit breaking action of the shaft carrying the selectors is controlled by an adjustable breaking means.

12. A device in accordance with claim 8 in which the indicating lamp functions to indicate proper tuning of a station irrespective of whether the selection thereof was manual or automatic.

13. A claim in accordance with claim 8 in which a pause period is created within the group of selected stations by means of a mechanism becoming effective at the expiration of fixed time intervals which may be made successive.

JOHN E. McCARTHY.
